APPARATUS FOR EXTRACTING WATER
FROM A WET TEXTILE AND THEN DRY-
ING THE SAME

Ernest A. Stienen, New York, N. Y.

Application January 2, 1935, Serial No. 22
In Germany September 25, 1933

3 Claims. (Cl. 34—26)

This invention relates to the apparatus for extracting water from a wet textile and then drying the same.

The object of the invention is the production of apparatus with which a wet textile and the like is subjected to a suction effect to extract the water therefrom, and subsequently dried by forcing heated fresh air therethrough.

The second object of the invention is the production of apparatus, whereby a plurality of wet textiles and the like, one after the other and continuously, first have the water therein extracted and then subsequently dried.

In the accompanying drawing Fig. 1 represents a section of Fig. 3 on the line 1.1 of an exemplification of the fluid extractor and drier for textiles; Fig. 2 shows a partial front view of the extractor and drier and a section of Fig. 3 on the line 2.2; Fig. 3 is a plan view of the extractor and drier, with a section on the line 3.3 of Fig. 1 and a section on the line 3a.3a of Fig. 2; Fig. 4 represents a section on the line 4.4 of Fig. 2; Fig. 5 indicates a fragmentary portion of Fig. 1 with its movable elements in a different position; and Fig. 6 shows an elevation of a modification.

A suction tank is designated in its entirety by the numeral 20, and comprises the cylindrical shell 21, the top wall 22 and the bottom wall 23. A pair of screens 24 and 25 extend across the interior of the tank 20. To the outer face of the top wall 22 is secured the conical shaped support 29, having the bottom flanges 30, through which extends the inlet conduit 31 and which has its upper end fastened to said support 29. The said conduit 31 extends through the screens 24 and 25 and has extending therefrom the valve rod support 32. From the inner face of the shell 21 extend the journal bracket 33 and the guide bracket 34. A lever 35 has its upper end pivoted to the journal bracket 33 and to its lower end is fastened the ball float 36. The lever 35 with its ball float 36 functions as a trap. A locking lever 38 is pivoted to the conduit 31 by means of the pivot 39 and has formed therewith the latch end 40. A vertical lever 41 has its lower end pivoted to the lever 35, by means of the pivot 42 and its upper end is pivoted to the locking lever 38, by means of the pivot 43. From the lower portion of the suction tank 20 extends the overflow piping 49 and to the latter is connected the spring controlled check valve 50.

Through the upper end of the shell 21 extends the T shaped valve chamber 52 which leads into the suction tank 20, having the valve seats 53 and 54 at its opposite ends. A conduit 55 having

the flange collar 56 at its end extends from the valve chamber 52. A T shaped inlet fitting 58 is indicated with the open end 59, which is connected to the valve chamber 52, and at the opposite end of the fitting 58 is shown the end wall 60. An inlet conduit 61 extends from the inlet fitting 58.

A valve rod is designated in its entirety by the numeral 65, and at one end thereof has the latch cavity 66, and its other end is threaded for the cap 67 and the locking nut 68. The valve rod 65 extends through the valve chamber 52, the inlet fitting 58 and the support 32. Valves 73 and 74 are fastened to the valve rod 65 and respectively actuate with the valve seats 53 and 54. A helical spring 75 encircles the valve rod 65 and its ends bear between the wall 60 and the cap 67.

A blower is designated in its entirety by the numeral 78, and is shown with the flange collar 79 at its inlet end, which is connected to the flange collar 56. The outlet conduit of the blower is shown at 80 with the flange collar 81. An outlet fitting 82 is interposed between the conduit 80 and the blower 78. A heating coil 85 for steam is positioned in the casing of the blower 78 and is indicated with the inlet piping 86 and the outlet piping 87.

An electric motor 90 has its armature shaft connected to the shaft of the propeller of the blower 78, by means of the coupling 91.

A drying tank is designated in its entirety by the numeral 95. The said drying tank comprises the cylindrical shell 96, having the flange 97 at its upper open end for the detachable cover 97a. The bottom wall for the tank 95 is shown at 98 having the opening 99 and an outlet sleeve 100 extends from the lower end of said tank 95. The flange collar 81 is connected to the wall 98.

Upon the wall 98 is supported the hollow pyramidal shaped support 105, having the bottom flange 106 and the outlet openings 107.

A rod 110 has its lower end connected to the support 105 and its upper end is threaded as shown at 111. A cap 112a is in threaded engagement with the threaded end 111 of the rod 110.

Referring to Fig. 1 a spool shaped material carrier is designated in its entirety by the numeral 115. The said carrier comprises the barrel 116, having the perforations 117 and the flanges 118 at its ends. To the flanges 118 are fastened the flanges 120. The carrier 115 has wound around its barrel 116 the textile 122.

The carrier 115 is positioned upon the suc-

tion tank 20, with one of its flanges 118 bearing on the bottom flange 30 of the support 29. Upon the flange 118 at the top end of the carrier 115 is positioned the cap 112 similar to the 5 cap 112a already described.

Referring to Fig. 2 a second spool shaped material carrier similar to 115 is designated in its entirety by the numeral 115a, and is indicated with its barrel 116a, having the perforations 10 117a and the flanges 118a and 120a. The textile 122a is wound around the carrier 115a. The carrier 115a is clamped in position by screwing the cover 112a to the upper end of the rod 110.

15 To operate the fluid extractor and drier, the carrier 115, having the wet textile 122 wound around its barrel 116, is positioned upon the suction tank 20, as shown in Fig. 1. The valve rod 65 is moved in the direction of the arrow A, Fig. 3, against the tension of the spring 75, until the latch cavity 66 is locked with the latch end 40 of the locking lever 38. In this position of the valve rod 65, the valve 73 is raised from its seat 53 and the valve 74 is seated on its seat 54. 20 The blower 78 is now turned by the electric motor 90 and air is sucked through the textile 122 as indicated by the arrows B, Fig. 1, and flows through the perforations 117 of the barrel 116. As the air flows through the textile 122 globules 30 of water from the moisture of said wet textile 122 is carried therewith. The mixture of the air and the globules of water drops through the conduit 31, as shown by the arrow C, into the suction tank 20. The air in the mixture, by 35 virtue of the increased diameter of the tank 20 over the diameter of the conduit 31, separates from the globules of water, which drop to the bottom of the tank 20. The air rises and flows through the screens 25 and 24, which also function to separate the air from the water globules. 40 The air is drawn through the valve chamber 52 and flows through the conduit 55 while it is pulled into and forced through the blower 78. It is evident that by the steps already described, 45 practically all of the water is extracted from the textile 122. The air as it flows through the blower 78 is heated by the heating coil 85 and is forced through the textile 122a in the drying tank 95. In the latter a carrier 115a with its 50 textile 122a is positioned, which has previously had its water extracted in the suction tank 20.

When the water has been extracted from the textile 122 the water level in the suction tank 20 has risen sufficiently to raise the ball float 36 55 to a height, whereby the latch end 40 is automatically unlocked from the latch cavity 66 and the tension of the spring 75 moves the valve rod 65 in the direction of the arrow G, Fig. 5. By this means the valve 73 is seated on its seat and the valve 74 is raised from its seat. In this position of the valves 73 and 74 no further suction effect is produced in the suction tank 20. When the water in the said tank 20 has risen to a predetermined level it is discharged therefrom 60 through the spring controlled check valve 50.

When the valve 73 is closed and the valve 74 is open, atmospheric air is pulled through the inlet conduit 61 in the direction of the arrow H, Fig. 3, and is sucked through and discharged 65 from the blower 78 and directed against the textile 122a in the drying tank 95. The air is heated by the heating coil 85 before it enters the drying tank 95, and is discharged from the latter through the outlet sleeve 100. The carrier 70 75 115a with its textile 122a is then removed from

the drying tank 95, and another carrier with its textile that has had its water extracted by means of the suction tank 20 and its appurtenances is positioned in the drying tank 95.

At the same time another textile with its carrier is placed in position on the tank 20 to have its water extracted by the suction tank 20 and its appurtenances.

The foregoing steps are repeated for a plurality of textiles one after the other, that are to have the water therein extracted and then dried.

Referring to Fig. 6, the invention is modified by eliminating the drying tank 95.

In this modification the outlet conduit of the blower is again shown at 80 with its flange collar 15 81. A disc 98a is shown on the collar 81. The pyramidal shaped support is again indicated at 105 with its rod 110. The material carrier is again shown at 115a. The cap for the carrier is again shown at 112a. The textile is shown at 122a. 20 In this modification the heated air is forced through the textile 122a directly into the atmosphere.

It will be noted that with the present invention the suction side of a blower is employed to extract 25 water from a wet textile and that the discharge side of said blower is used to force heated air through the textile that has had its water previously extracted. Heretofore a blower was employed for extracting the water from the textile 30 and a second blower was employed to blow the heated air therethrough.

Various modifications may be made in the invention and the present exemplification is to be taken as illustrative and not limitative thereof. 35

Having described my invention, I claim:

1. In a fluid extractor and drier for textiles and the like, the combination of a suction tank, a perforated carrier for the material to be treated detachably supported on the tank, a conduit connecting the interior of the carrier and the interior of the tank, a valve chamber connected to the tank, a valve for the valve chamber, means to manually raise said valve from its seat, automatic means in said tank controlled by the level of the 40 fluid in the tank to close said valve and a blower in connection with said valve chamber to produce a suction effect in said tank.

2. In a fluid extractor and drier for textiles and the like, the combination of a suction tank, a 50 perforated carrier for the material to be treated detachably supported on the tank, a conduit supported in the suction tank connecting the interior of the carrier and the interior of the tank, a valve chamber connected to and leading into the 55 tank, a valve seat at the end of the valve chamber where it leads into the suction tank, a valve rod extending through said valve chamber and into the suction tank, means to slidably support the valve rod, said valve rod having a latch cavity 60 adjacent to its end in the suction tank, a valve carried on the valve rod coacting with said valve seat, a locking lever pivoted to said conduit, a latch end integral with said locking lever coacting with the latch cavity of said valve rod, means to manually lock said latch end to said latch cavity, a trap in the suction tank actuated by the fluid therein extracted from the material operated upon, a lever connecting said trap and said locking lever, a blower and a conduit connecting said valve chamber and the inlet end of the blower, said blower producing a suction effect in said suction tank. 70

3. In a fluid extractor and drier for textiles 75

and the like, the combination of a suction tank for a material to be operated upon, a valve chamber connected to and leading into the tank, a valve seat at each end of the valve chamber, a valve coacting with each valve seat, an inlet fitting for air connected to said valve chamber, one of said valves interposed between said valve chamber and said tank, said other valve interposed between said valve chamber and said fitting, means to manually open the valve for the tank and simultaneously close the valve for said fitting, automatic means controlled by the level

5 of the water in the suction tank extracted from the material operated upon to reverse the positions of the valves and a blower connected to said valve chamber to produce a suction effect in said suction tank and a second tank connected to the outlet end of said blower, said blower and valve chamber with its valves adapted to draw vapor from said suction tank and force it into the second tank, or to force air into the second
